US0D1067772S

(12) **United States Design Patent** (10) **Patent No.:** **US D1,067,772 S**
(45) **Date of Patent:** **** Mar. 25, 2025**

(54) **LID**

(71) Applicant: **YETI Coolers, LLC**, Austin, TX (US)

(72) Inventors: **Dustin Bullock**, Austin, TX (US);
Colin Darling, Austin, TX (US); **Evan Goldberg**, Austin, TX (US); **Hector Barea**, Austin, TX (US)

(73) Assignee: **YETI Coolers, LLC**, Austin, TX (US)

(***) Term: **15 Years**

(21) Appl. No.: **29/908,288**

(22) Filed: **Jan. 11, 2024**

Primary Examiner — Andrew Kerr

Assistant Examiner — Courtney J Clark-Rasheed

(74) *Attorney, Agent, or Firm* — Banner & Witcoff, Ltd.

(57) **CLAIM**

The ornamental design for a lid as shown and described.

DESCRIPTION

FIG. 1 is a front top perspective view of a lid showing our new design;

FIG. 2 is a rear bottom perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The broken lines represent portions of the lid that form no part of the claimed design.

1 Claim, 5 Drawing Sheets
